ABSTRACT

A twirling baton with a sturdily mounted side handle to enable a novice, as well as a professional, to twirl the same for long periods of time with little effort or attention. In one embodiment, the handle is removable so that the baton may be twirled in a normal manner. One end of the baton is weighted to increase momentum during twirling, and the handle includes bearings to reduce friction.

TWIRLING BATON

BACKGROUND OF THE INVENTION

The present invention relates to batons and more particularly to the type twirled by drum majors, majorettes and the like.

Twirling batons are used by persons having a wide range of dexterity in the art of twirling and this includes children with toy batons to professional drum majors or majorettes. In addition, there are baton twirling corps of all ages that engage in competition and in marching demonstrations. It is desirable that a baton be easily twirled by the inexperienced person, or in an effortless manner for long periods of time by the more experienced persons.

For this reason, several types of batons have been developed having a handle attached to the baton shaft whereby baton twirling may be simulated without the usual energy and concentration of real twirling.

Typical of these patents are: D. A. Harrold, et al., U.S. Pat. No. 2,812,683, "Baton," issued Nov. 12, 1957; J. Kaplan, U.S. Pat. No. 2,918,839, "Twirling Baton," issued Dec. 29, 1959; and E. J. Rohmann, U.S. Pat. No. 2,988,949, "Baton," issued June 20, 1961. These patented devices suffer from several deficiencies; principally, none of these prior art provide for detachment of the handle so as to provide a conventional baton. Also, the bearing surfaces are such that the handle may become wobbly after extended use.

SUMMARY OF THE INVENTION

The disadvantages of the prior art are overcome by providing a handle having a central nonrotating spindle, a housing rotatable about the spindle and bearing members interposed between the spindle and the encircling housing. This handle may be permanently fastened to the baton shaft at its midpoint or may be easily released therefrom to provide a conventional baton.

BRIEF DESCRIPTION OF THE DRAWINGS

FIG. 1 is a cross-sectional view of one embodiment of the present invention with portions of the baton shaft removed to provide clarity to the essential components of the invention;

FIG. 2 is a cross-sectional view of a second embodiment of a handle for the present invention;

FIG. 3 is a cross-sectional view of still another embodiment of a handle; and

FIG. 4 is a cross-sectional illustration of an additional embodiment of the invention.

DETAILED DESCRIPTION

Referring to FIG. 1, a hollow baton shaft 1 of conventional dimensions; e.g., about 27 inches long by 9/16-inch diameter, has inserted in one end thereof a weight 2. The weight 2 and a portion of this end of shaft 1 are encased in a conventional resilient knob 3. The opposite end of shaft 1 is encased in a second conventional resilient knob 4 of lesser mass. A non-rotatable spindle 5 is attached perpendicularly to shaft 1 at the midpoint between the ends of the shaft. This spindle 5 is divided into unequal lengths 6, 7 by a shoulder 8. The short portion 6 of the spindle, which may be circular or square in cross section, passes through close fitting holes in the shaft 1 to completely penetrate the shaft 1, and is joined to the shaft 1 as at 9 by welding, brazing or other permanent means.

Spaced from and encompassing the long portion 7 of spindle 5 is a cylindrical housing 10. The spacing is governed by, in this embodiment, a pair of bearing members 11, 12. Sleeve bearings, or a continuous bearing surface might equally be used. Bearing 11 abuts shoulder 8 to prevent axial movement of housing 10 toward the shaft 1, and a snapring 13, engaging a recess 14 in spindle 5, prevents movement of bearing 12 or housing 10 in a direction away from shaft 1. A handle grip 15 is fractionally fit over the housing 10.

My improved baton is twirled with little effort by grasping the handle firmly and initiating the spinning of the shaft 1 as by pushing with my index finger against the side of shaft 1. Then with only a slight wrist movement, twirling can be continued as a certain unbalanced momentum is given by weight 2. The rotational plane of the baton may be changed by twisting my wrist, and thus most movements of a real twirling baton may be simulated.

A second embodiment of a handle for my twirling baton is illustrated in FIG. 2. In this embodiment, the short portion of spindle 5 is omitted and the shoulder 8 is permanently joined to a cylindrical collar 16. This collar encircles and is permanently (or semipermanently) attached at the midpoint of shaft 1. The internal components of the handle are the same as in FIG. 1. This embodiment provides for the attachment of the handle unit to any baton shaft. Operation of the baton is the same as described above.

Another baton and handle embodiment is shown in FIG. 3 with provision for removal of the handle when desired so as to have a conventional baton. In this embodiment, a cylindrical bushing 17 is inserted into the shaft 1 and fastened in any manner at the midpoint between the ends of the shaft 1. This bushing is provided with a transverse channel 18 having equal flat surfaces, e.g., four equal surfaces, to receive the short portion 6' of spindle 5. This short portion 6' has exterior flat surfaces corresponding to the interior of channel 18. Mounted in one flat surface of short portion 6' of spindle 5 is a detent element consisting of a ball 19 and spring 20. Other forms of detents could be utilized with equal results. Each of the surfaces of channel 18 contain a recess 21 to receive ball 19 when the handle is to be attached to shaft 1. Only two recesses 21 are illustrated in this figure, and take the form of cylindrical passageways. This combination of one detent but a plurality of recesses permits insertion of the spindle short portion 6' into channel 18 in several orientations, the member depending upon the number of flat surfaces in channel 18. Also, the spindle is made nonrotating through the use of flat surfaces.

The operation of this embodiment is the same as that for the embodiments of FIGS. 1 and 2 except that the handle may be removed. This removal is accomplished by pushing against shaft 1 in a direction parallel to the axis of spindle 5. This disengages the ball 19 from a recess 21 and the handle is removed. This construction is particularly useful for a drum major or majorette during a long parade. During periods of routine marching, the handle may be attached and the baton twirled without close attention. Then while passing a judging stand or other position where twirling ability is to be demonstrated, the handle may be removed, stored in a pocket, and the baton shaft twirled in a normal manner.

The above-described ball detent attachment is only one of several methods of releasably attaching the handle to the shaft of my baton. For example, a bayonet-type connection as shown in FIG. 4 may be used: A bushing 22 would be mounted in the shaft 1 which has a cylindrical channel 23 oriented perpendicularly to the axis of the shaft. One or more grooves 24 would be formed in the surface of this channel for receiving one or more projections 25 on the short end 26 of the spindle 7. Each groove 24 would have a generally perpendicular offset 27 so that a twisting motion of the spindle, as by twisting on the spindle shoulder 8, moves the spindle projection 25 into the offset 27. A spring member 28 would be provided either in the closed end of the channel, or in the end of the spindle as shown, to ensure frictional contact of the spindle projection 25 in the offset 27. The handle would be released from the shaft by compressing the spring 28 and releasing the projections 25 from the offsets 27 so as to permit removal of the spindle end 26 from the channel 23.

My baton has several features and advantages over those of the known prior art. It is extremely rugged and will function satisfactorily for many years. Furthermore, there are no sharp protrusions or edges to damage the hand of the operator. A special feature is the removable handle for uses as described above or to permit a beginner to initially twirl a baton using

the handle but remove the handle when more proficiency is attained.

I claim:

1. A twirling baton comprising:
  - a. an elongate shaft;
  - b. a cylindrical bushing mounted centrally within said shaft having a transverse spindle-receiving channel oriented perpendicularly to said shaft;
  - c. a nonrotatable removable handle spindle projecting from said channel in said bushing; and
  - d. releasable locking means associated with both said spindle and said channel to secure or release said spindle within said channel.
2. The twirling baton of claim 1 wherein said channel is provided with at least one recess in the surface thereof, and said spindle is provided with at least one projection extending per-

pendicularly thereto for releasable engagement with said recess to thereby comprise said releasable locking means.

3. The twirling baton of claim 2 wherein said channel has equal flat surfaces; said recess is circular in cross section; said spindle has flat surfaces at one end thereof equal in number to those of said channel for slideable engagement therewith; and said projection on said spindle is a ball detent to releasably engage said recess.
4. The twirling baton of claim 2 wherein said recess in said channel is a longitudinal slot having an offset perpendicular thereto; said projection on said spindle releasably engages said offset; and further comprising a spring member within said channel to increase frictional engagement of said projection in said offset to releasably attach said spindle within said channel.
